UNITED STATES PATENT OFFICE.

KARL ROSTEL, OF MONESSEN, PENNSYLVANIA.

DRY-CLEANING DEVICE.

1,043,730.

Specification of Letters Patent.

Patented Nov. 5, 1912.

Application filed July 29, 1912. Serial No. 712,061.

To all whom it may concern:

Be it known that I, KARL ROSTEL, a citizen of the United States of America, residing at Monessen, in the county of Westmoreland 5 and State of Pennsylvania, have invented certain new and useful Improvements in Dry-Cleaning Devices, of which the following is a specification, reference being had therein to the accompanying drawing.

10 This invention relates to a dry cleaning device, and the primary object of my invention is to provide a device embodying a yieldable absorbent cleansing head to which gasoline or a suitable detergent can be fed 15 for cleaning purposes.

Another object of this invention is to provide a dry cleaning device having a detachable cleansing body that can be renewed when worn or soiled or a different type of 20 head substituted, as a piece of material to be cleaned may require.

A further object of this invention is to provide a tool for cleaning various kinds of fabrics that can be easily and safely manipulated in an expeditious manner.

With the above and other objects in view the invention resides in a novel construction, combination and arrangement of parts to be hereinafter specifically described and then 30 claimed.

Reference will now be had to the drawings, wherein:

Figure 1 is a side elevation of the cleaning device, partly broken away and partly 35 in section, Fig. 2 is a plan of the same, Fig. 3 is a perspective view of a discharge head forming part of the device, and Fig. 4 is a perspective view of a detached spacing plate.

The reference numeral 1 denotes a T having one end thereof provided with a handle 2 and the opposite end thereof with a pet cock 3. The top of the T supports a reservoir 4 having a detachable screw cap 5. The cap 5 has a vent opening 6 that can be closed 40 by a pivoted shutter 7, carried by the cap 5 and limited in its movement by stops or pins 8. The reservoir is preferably made of a transparent material, as glass and gasoline or a liquid detergent can be placed in the 45 reservoir and fed to the pet cock by opening the vent 6.

The pet cock 3 has a discharge spout 9 terminating in a rectangular head 10 that has the vertical edges thereof slightly curved, as 55 shown in Fig. 2. The head 10 is provided with an outlet opening 11 and with an

outwardly extending integral screw threaded stem 12. The outer side of the head 10 has vertically disposed ribs 13 providing a vertical channel 14 that is in communication 60 with the opening 11 of the head.

Arranged against the head 10, upon the stem 12 is a spacing plate 15 that is rectangular and has an opening 16 providing clearance for the stem 12. The plate 15 is 65 made of a resilient material and is clamped against the ribs 13 by a yieldable absorbent cleaning head 17 made of a piece of absorbent material wound to provide a roll, the cleaning head 17 having an opening 18 providing clearance for the stem 12. The cleaning head is compressed upon the stem 12, against the spacing plate 15 by a curved clamping plate 19 that is arranged upon the threaded end of the stem 12 and held thereon by a nut 20 screwed upon said stem. In pressing the clamping plate 19 against the head 17, the head 17 is compressed to an oval 70 form, as shown in Fig. 2, the lower end of said head having a mushroom shape. 80

By opening the vent 6 and regulating the pet cock 3 a quantity of gasoline or liquid detergent is allowed to flow from the opening 11 into the channel 14 and on to the lower end of the cleaning head 17, to be absorbed by said head, whereby the head can be rubbed upon a piece of fabric to remove stains, dirt and other matter that can be removed from the fabric by the detergent 85 that is used. 90

When the cleaning head is worn or soiled, it can be easily removed and a new head substituted therefor.

It is apparent that by using the cleaning device that there is a saving of gasoline, 95 owing to the fact that the volume of gasoline is inclosed and cannot rapidly evaporate, also the supply of gasoline to the cleaning head can be regulated to prevent waste.

It is thought that the manner of using the device will be apparent without further description, and I would have it understood that the structural elements are susceptible to such variations as fall within the scope of the appended claims. 100 105

What I claim is:

1. A dry cleaning device comprising a pet cock, a reservoir in communication therewith, a discharge head carried by said pet cock, a stem forming part of said discharge head, a spacing plate arranged upon said stem, and a wound cleaning head arranged 110

upon said stem and clamped against said spacing plate.

2. A dry cleaning device comprising a pet cock, a reservoir in communication therewith, a discharge head carried by said pet cock and having a channel formed therein, a stem carried by said discharge head, a wound yieldable cleaning head arranged upon said stem, and means for compressing and clamping said cleaning head against said spacing plate.

3. A cleaning device comprising a T, a handle carried thereby, a reservoir in communication with said T and having a vent, a pet cock in communication with said T, a discharge head carried by said pet cock and having a channel formed therein, a stem

carried by said discharge head, a spacing plate arranged upon said stem, a wound yieldable and absorbent cleaning head arranged upon said stem and against said spacing plate and adapted to receive the contents of said reservoir through the medium of said pet cock and the channel of said discharge head, and means including a clamping plate for compressing and retaining said cleaning head upon said stem and in engagement with said spacing plate.

In testimony whereof I affix my signature in the presence of two witnesses.

KARL ROSTEL.
